UNITED STATES PATENT OFFICE.

WILLIAM F. WENDT, OF BUFFALO, NEW YORK, ASSIGNOR TO BUFFALO FORGE COMPANY, OF BUFFALO, NEW YORK.

FORGE.

No. 805,691.

Specification of Letters Patent.

Patented Nov. 28, 1905.

Application filed March 6, 1905. Serial No. 248,681.

To all whom it may concern:

Be it known that I, WILLIAM F. WENDT, a citizen of the United States, residing at Buffalo, in the county of Erie and State of New York, 5 have invented a new and useful Improvement in Forges, of which the following is a specification.

This invention relates to blacksmiths' forges, and more particularly to the portable kind 10 which are set up in the shop or room at a distance from the chimney and are provided with hoods for catching and directing the smoke and gases from the fire to the smoke-pipe. These hoods are usually faulty or objectionable, in 15 that they either fail to properly catch and carry off the smoke and gases arising from the fire or, on the other hand, if they are properly shaped and located to carry off all of the smoke and gases they so obstruct the hearth of the 20 forge as to materially interfere with the blacksmith's operations.

The objects of the invention are to provide a forge with means which will efficiently catch and carry off the smoke and gases without obstructing the hearth or fireplace and to so construct and arrange the hood or smoke-catcher that it will operate to catch and carry off the smoke and gases either with or without means for creating a forced draft in the smoke-flue. 25

30 In the accompanying drawings, consisting of two sheets, Figure 1 is a fragmentary perspective view of a forge embodying the invention. Fig. 2 is a fragmentary plan view thereof, partly in horizontal section, in line 2, 2, 35 Fig. 4. Fig. 3 is a transverse sectional elevation through the upright smoke-flue in line 3, Fig. 4. Fig. 4 is a fragmentary longitudinal sectional elevation of the forge.

Like letters of reference refer to like parts 40 in the several figures.

The forge, which may be either of the stationary or portable type, has a hearth A of any usual or suitable form and construction, which is supported by legs a or some other kind of 45 base.

B represents the usual fireplace in the hearth provided with a blast-twyer b, and C represents a fan-blower or air-forcing device, the air-discharge or blast pipe c of which connects 50 with the twyer b. The blower may be of any usual form and operated by any suitable means.

D represents the smoke hood or catcher,

which is arranged above the hearth and overhangs the fireplace B. The hood is preferably of the hollow rectangular shape shown, having a horizontal top with depending front and side walls and is supported by an upright back e, which rests on or is secured to and rises from the hearth in rear of the fireplace. The 55 back e of the smoke-hood is hollow, forming an ascending smoke-flue F, provided in its front wall with a smoke-inlet opening f, which is located just in rear of the fireplace B and only a short distance above the hearth. The 60 upper open end of the smoke-flue F enters or communicates with a smoke-pipe G, which leads from the top of the hood D to the chimney. The hood also opens into the lower end of the smoke-pipe independently of the 65 upright smoke-flue, so that the smoke and gases from the fire can pass into the smoke-pipe either directly from the hood or indirectly by way of the inlet-opening f and upright flue F. The flue could, if desired, be formed by a separate pipe occupying the same position as the 70 hollow back of the hood.

H represents a shield or auxiliary hood which projects forwardly from the upright smoke-flue F above the inlet-opening f thereof and beneath the main hood D. The shield or auxiliary hood H is preferably smaller than the main hood and adjustably mounted so that its position or inclination can be adjusted to properly direct the smoke and gases into the 85 inlet-opening f. In the construction shown the shield is hinged at the front side of the upright flue F, and its hinge pin or shaft is extended through the side of the hood and provided with an operating-arm h, furnished with 90 any suitable means h' for releasably holding it and the shield in adjusted positions.

Preferably the eye or intake of the blower C is connected with the lower end of the upright smoke-flue F by a suction-pipe I, and a 95 branch pipe K discharges a portion of the air-blast from the blower into the smoke-pipe G to induce an upward draft therein. The open upper end of the branch pipe K preferably terminates in the smoke-pipe substantially at 100 the upper end of the upright smoke-flue F and also creates an induced draft in the latter. The separate pipe K (shown in the drawings) or a flue partitioned off in the upright smoke-flue can be employed for this purpose. By 105 reason of the described arrangement of the

suction and blast pipes of the blower a portion of the smoke and gases is drawn into the blower and returned to the fire and a portion passes upwardly into the smoke-pipe under the influence of the induced draft therein. The proportion of these parts can be regulated, if found necessary, by providing the suction and blast pipes with dampers.

The operation of the forge is as follows:

5 When a green fire is started and the blower is operated at a comparatively slow speed, the dense smoke generated is drawn into the inlet-opening *f* of the upright flue *F* by the suction and induced draft in the latter caused by the blower. The smoke from the extreme front end of the fire will be caused to hover close to the coal and travel rearwardly into the inlet-opening. None, or at least only an inconsiderable portion, of the smoke and gases

10 will escape past the shield *H*, but that which does will be caught by the hood and drawn into the open lower end of the smoke-pipe. With only the main hood *D* opening so far above the hearth as it should in order not to interfere with the blacksmith's operations it would be impossible to create the necessary suction at the fire to hold this smoke and prevent its escape into the room or shop. Then as the speed of the blower is increased and

15 the volume of dense smoke and gases is considerably augmented only a portion thereof will pass up through the upright smoke-flue *F* and the remainder will be caught by the main hood *D* and pass directly up into the smoke-pipe *G*. Under these conditions without the large main hood *D* a large volume of the smoke and gases would escape into the shop. Thus neither the main hood nor the upright flue with the shield *H* alone will properly take care of the smoke and gases, and the two associated as described are necessary to a realization of the desired result. Later when the coal becomes coked the flame and gases will pass out through the opening *f* and upright flue *F*. When the blower is out of action, the draft created by the chimney will take care of the smoke and gases arising from the fire.

While greater perfection of operation of the forge will result from the use of the suction and blast pipes *I* and *K*, as described, the main hood or smoke-catcher with the upright smoke-flue and shield or auxiliary hood when used independently of the suction and draft inducing means are a marked improvement over a single hood in either the location of the main hood *D* or auxiliary hood *H*.

L, Fig. 4, represents a plate or apron hinged to the hood *D* and adapted to be turned down, as indicated by dotted lines in Fig. 1, when starting a fire or to be turned up out of the way after the fire is started. Such plates may, if desired, be provided at the front and one side of the hood; but they are not essential to the proper operation of the forge.

I claim as my invention—

1. The combination of a hearth having a fireplace, a smoke-hood above the hearth, a smoke-pipe ascending from said hood, and an ascending smoke-flue which has a smoke-inlet opening located adjacent to the fireplace, said flue connecting at its upper portion with said smoke-pipe, substantially as set forth. 70

2. The combination of a hearth having a fireplace, a smoke-pipe, a hood above the hearth for directing the smoke into the lower portion of said smoke-pipe, an ascending smoke-flue which has a smoke-inlet opening located adjacent to the fireplace, said flue connecting at its upper portion with said smoke-pipe, and means for causing the smoke to enter said inlet-opening of the ascending smoke-flue, substantially as set forth. 75
80

3. The combination of a hearth having a fireplace, a smoke-hood above the hearth, a smoke-pipe ascending from said hood, an ascending smoke-flue located at one side of the fireplace and having a smoke-inlet opening adjacent to the fireplace, and means for directing the smoke from the fire into said opening, substantially as set forth. 85
90

4. The combination of a hearth having a fireplace, a smoke-hood above the hearth, a smoke-pipe leading from said hood, an ascending smoke-flue having a smoke-inlet opening located at one side of and adjacent to the fireplace, said flue connecting at its upper portion with said smoke-pipe, and a shield above said inlet-opening for directing the smoke from the fire into said flue, substantially as set forth. 95

5. The combination of a hearth having a fireplace, a smoke-hood above the hearth, a smoke-pipe leading from said hood, an upright smoke-flue located at one side of the fireplace and having a smoke-inlet opening adjacent to the fireplace, and a shield of smaller dimensions than said hood adjustably mounted over said opening for directing the smoke from the fire into said opening, substantially as set forth. 105
110

6. The combination of a hearth having a fireplace, a smoke-hood above the hearth having an upright hollow back located in rear of the fireplace and provided in its front wall with a smoke-inlet opening adjacent to the fireplace, a smoke-pipe leading from said hood and connecting with the said hollow back, and a shield above said inlet-opening for directing the smoke from the fire into said opening, substantially as set forth. 115
120

7. The combination of a hearth having a fireplace, a smoke-hood above the hearth, a smoke-pipe ascending from said hood, an ascending smoke-flue located at one side of the fireplace and having a smoke-inlet opening adjacent to the fireplace, means for directing the smoke from the fire into said opening, and an air-forcing device connecting with said fireplace and provided with means for inducing 125
130

an upward draft in said smoke pipe and flue, substantially as set forth.

8. The combination of a hearth having a fireplace, a smoke-hood above the hearth, a smoke-pipe leading from said hood, an ascending smoke-flue located at one side of the fireplace and having a smoke-inlet opening adjacent to the fireplace, means for directing the smoke from the fire into said opening, a blower connected with said fireplace, and a suction-pipe connecting the intake of said blower with said upright smoke-flue, substantially as set forth.

9. The combination of a hearth having a fireplace, a smoke-hood above the hearth, a smoke-pipe leading from said hood, an upright

smoke-flue located at one side of the fireplace and having a smoke-inlet opening adjacent to the fireplace, means for directing the smoke from the fire into said opening, a blower having a blast-pipe leading to the fireplace, a blast-pipe for inducing an upward draft in said smoke pipe and flue, and a suction-pipe connecting the intake of said blower with said upright smoke-flue, substantially as set forth. 20 25

Witness my hand this 21st day of February, 1905.
